(57) CLAIM

The ornamental design for a cart storage station, as shown and described.

DESCRIPTION

FIG. 1 is a front perspective view of a cart storage station according to our new design;

FIG. 2 is a front view of the cart storage station of FIG. 1; FIG. 3 is a right side view of the cart storage station of FIG. 1;

FIG. 4 is a rear view of the cart storage station of FIG. 1; FIG. 5 is a left side view of the cart storage station of FIG. 1; and,

FIG. 6 is a top view of the cart storage station of FIG. 1. The broken lines depict portions of the cart storage station that form no part of the claimed design.
